DOBBY OR JACQUARD OF WEAVING-LOOMS.

1,177,343.

Specification of Letters Patent. Patented Mar. 28, 1916.

Application filed January 22, 1912. Serial No. 672,636.

To all whom it may concern:

Be it known that I, GEORGES ELIE LEVY, a citizen of the Republic of France, and a resident of Paris, France, have invented certain new and useful Improvements in or Relating to Dobbies or Jacquards of Weaving-Looms, of which the following is a specification.

This invention relates to improvements in double shedding motion for dobbies or jacquards of weaving looms of the type described in the United States Patent No. 987,086, of March 14, 1911. In the said patent, the shedding bars are mounted in such a way as to slide upward and downward or inversely on a needle-bar; the latter slides transversely from left to right or inversely, at the required moment, by a needle subjected to the action of a needle-card, said needle being engaged by a spring-pressed needle-bar. The objection to this arrangement is that the transverse sliding of the shedding bar being at right angles relatively to the traction of the cords connecting said shedding bars to the rocking levers of the loom, said cords are taut and must stretch each time to permit the transverse sliding of the shedding bars. This precludes the employment of metallic connecting bars for connecting the shedding bars with said rocking levers. Furthermore, the needle-card, for sliding the shedding bars, must overcome this tension of the cords, and this is liable to injure the needle-card.

The present invention consists in mounting the shedding bars on supports, directly connected by metallic connecting bars with the rocking levers; each shedding bar slides transversely, from left to right, and inversely on its support which serves as a guide, while the support always remains in alignment with the traction of the connecting bars. In order to facilitate the transverse sliding of the shedding bar in its support, the shedding bar and the support are provided with inclined engaging surfaces. By thus mounting the shedding bar it acts only as a controlling and hooking bar.

On each of the lowering and lifting knives is provided, an auxiliary knife, the purpose of which is to retain the shedding bars, when they are no longer hooked by said lowering and lifting knives, to prevent them from returning too suddenly under the effort of the tension of the warp thread passed in

the heddle of the harness of the loom, to the position of the closed shed, that is to say to the intermediate position between that of the lifting and that of the lowering. Said auxiliary knives accompany the shedding bars and hold them to half of their course, that is to say, up to the moment where the tension of the warp threads cease exerting an action on the shedding bars.

On the annexed drawing: Figure 1 is an elevation showing in full lines the shedding bar provided with its support and hooked to its lowered position; the dotted lines indicate the same shedding bar unhooked and ready to be lifted. Fig. 2 is a transverse section on the line 2—2 of Fig. 1; Fig. 3 shows, in part, two shedding bars, on a larger scale for allowing to see the arrangement of the control of the auxiliary knives, the front shedding bar being lifted and the rear one being lowered at the moment supposed of their unhooking, that is to say, in the position where the auxiliary knives hold them; Fig. 4 shows the shedding bars hooked, after the auxiliary knives have released them, the front shedding bar being hooked in its lower position and the rear one in its lifted position; Fig. 5 shows, in elevation, the whole of the motion, with a shedding bar provided with its support, hooked at its lowered position; and Fig. 6 is a detail view showing the stops and how they are supported.

In said figures, for a better understanding of the drawing, two shedding bars only are shown, but it is obvious that the loom may have any number.

Referring to the drawing, each heddle *a*, of which the whole constitutes the harness of the loom (see Fig. 5) is connected to a rocking lever *b* and to the upper part and to the lower part of the shedding bar sliding on a needle bar *d*. The needle bar is provided with two lugs *d*² engaged in the grooves *c*² of the shedding bar, so that the shedding bar *c* partakes of the motions communicated to the needle bar *d* by the needle *e* sliding in the plate *d*⁴ and engaged by the front end *d*³ of the needle bar *d*. The needle bar *d* is guided by a rod *d*⁵, carried by the needle bar and sliding in a plate *d*⁶ and a spring *d*⁷, surrounding the said bar *d*⁵ between the needle bar *d* and the plate *d*⁶, holds the front end *d*³ of the needle bar constantly in engagement with the needle *e*.

The shedding bar *c* has a notch *c*³ engaged

by a spring pressed latch f f' for the purpose of engaging and holding the shedding bar in its lowered position; an inclined projection c^4 on which a movable bar g acts and 5 called unhooking bar for lifting the shedding bar when it is hooked on its lifted position; a notch c^5 for the lifting knife k ; a notch c^6 for the lowering knife l ; and a notch c^7 engaged by a spring pressed latch 10 h h' for hooking the shedding bar when in its lifted position.

The needle card i acts in the regular way on the needles e and can be brought nearer or driven away from said needles by the controlling contrivance j in order to permit the 15 changing of the card.

In the position shown in Figs. 1 and 5 as well as in Fig. 4, the shedding bar c is hooked in its lowered position, that is to say, 20 the corresponding heddle a is in the lifting position (Fig. 5) while the shedding bar c^1 (Fig. 4) is hooked in its lifted position, the corresponding heddle a^1 being then at its lowered position (Fig. 5).

25 Let us suppose that the needle e of the shedding bar c is in front of a hole of the card i (Fig. 5), the needle of the shedding bar c^1 being before a solid part, the spring d^7 will cause the needle e to enter the perforation of the needle card i and will thus hold 30 the notch c^3 of the shedding bar c in engagement with the latch f , and the shedding bar c will remain at its lowered position. At the same time, the unhooking bar g will 35 lift the shedding bar c^1 , but the needle of the latter meeting a solid part of the card, this shedding bar will not be able to slide transversely and the notch c^7 of this shedding bar c^1 will drop in engagement with 40 the latch h , the shedding bar c^1 thus remaining at its lifted position.

If the needle card is changed in such a way that the needle e of the shedding bar c meets a solid part, and the needle of the 45 shedding bar c^1 meets a hole of the card, when the cylinder comes to rest again, under the action of the controlling contrivance j , the following effect is obtained: The needle e is laterally pushed, as well as the needle-bar d , and the shedding bar c in the position shown in dotted lines in Fig. 1 (that is to say toward the right, Fig. 4), compressing the spring d^7 ; while the shedding bar c^1 , the needle of which meets a hole of 50 the card, can be pushed back in a contrary direction by the tension of the corresponding spring d^7 , when the unhooking bar g lifts the shedding bar c^1 by the notch c^4 , in such a way that the notch c^7 of this shedding bar c^1 can be released from the latch h . The knife k , which at that moment lifts, 55 meets the notches c^5 of the shedding bar c (Fig. 1) and lifts the latter until hooking its notch c^1 on the latch h ; the shedding bar c is thus brought to its lifting position. The

shedding bar c^1 , by its transverse sliding, comes in the line of travel of the lowering knife l , which, engaging the notch c^6 , causes said shedding bar c^1 to descend and to hook it at its lowered position, by means of the latch f engaging the notch c^3 , the shedding bar c^1 being held by the spring d^7 in such a way that it cannot be lifted under the action of the lifting knife k , but the corresponding needle, meeting a solid part of the card, 70 presses said spring d^7 and disengages the shedding bar from the latch f . In the same way, the shedding bar c engaged by its notch c^7 with the latch h , will not be able to descend, under the action of the lowering knife l , but when its needle e meets a hole of the card, will be released from the latch h by the lifting motion of the bar g ; this unhooking position is shown in Fig. 3. The 75 motions are thus reproduced, the lifting knife k dragging the lowered shedding bar, which must be lifted and hooks them on the latch h , while the lowering knife l drags the lifted shedding bar which must be lowered 80 and hooks it on the latches f .

The transverse sliding of the shedding bars required for producing their unhooking, being at right angles relatively to the traction of the members connecting the shedding bars to the rocking levers of the motion, produce a tension upon said members, and consequently the latter must be elastic 95 in order to permit of this movement; furthermore, the needle card for sliding the shedding bars, must overcome this tension 100 and this injures the card.

The construction so far described is all old, being substantially the same as that shown in the hereinbefore mentioned patent. According to the present invention, the 105 shedding bars c , are mounted (see Figs. 1, 2 and 3), on supports serving as guides and which always remain in the vertical plane in which the traction is exerted on the members connecting the shedding bar to the 110 rocking levers. These members can consequently be made of metallic connecting bars z . These supports each consist of two central members m having eyes m^1 , with which engage the ends of the connecting bars z , 115 and two bracket members m^2 , one of which connects the member m and the other terminates near the inner ends of said members in such a way as to leave room for the needle bar d . The members m are formed with 120 inclined ways, respectively m^3 , m^4 with which the inclined ends of the shedding bar c engage. The inclination of said ways and ends of the shedding bars is such that they facilitate the sliding of the shedding 125 bars c laterally. One of the members m^2 at each end of the support, is provided with an edge portion m^5 , said portions serving as stops to limit the sliding of said shedding bar, before the lifting of the lowering 130

knife acts on the latter. When the shedding bars are hooked, either in their lowered position, or their lifted position, the warp threads, passing through the heddles a , a^1 , 5 constituting the loom harness, exert a tension on said heddles to bring them back to an intermediate position to the lowered or lifted position, that is to say, to the position of the closed shed, (shown by A—A 10 of Fig. 5). This tension is exerted by the rocking levers b and the connecting bars z on their supports. When the shedding bar c is hooked, as shown on Figs. 1 and 5, in its lowered position, the warp threads exert a 15 tension on the lifted heddle a (Fig. 5) and tends to lower it in the direction of the arrow x ; this forces the support m also in the direction of the arrow x by the action of the connecting bars z . 20 When the needle e meets a solid part of the card i , the shedding bar c is pushed laterally toward the left of Fig. 1, and thus causes the unhooking of the said shedding bar c . The support under the action of the 25 connecting bar z at the upper end thereof, acts by its inclined way m^3 on that of the shedding bar and thus facilitates the lateral sliding of the latter under the action of the pressure of the card i on the needle e 30 and the shedding bar is brought to the position shown on the dotted lines (Fig. 1) where it presents its notch c^5 to the lifting knife k .

The inverse effect is produced for the 35 hooked shedding bar in its lifted position, that is to say, when the heddle a^1 is at its lowered position. It is then that the inclined way m^4 of the support m acts on the inclined end of the shedding bar, being 40 urged by the connecting bar z at the lower end of the support together with the tension of the warp thread on the heddle a^1 , and causes the transverse sliding of the shedding bar from the position in dotted 45 lines to the position shown in full lines, in order that it presents its notch c^6 to the lowering knife l .

With this arrangement only the supports slide in the direction of the traction of the 50 connecting bars z , the shedding bars merely acting as hooking bars.

Under the effect of the tension of the warp thread on the heddle a , a^1 , the shedding bars are urged to abruptly return to 55 the position of the closed shed as soon as they are unhooked (see Fig. 3), and to avoid this abrupt motion, auxiliary knives l^2 and l^3 are mounted on the lifting and lowering knives k and l , respectively. The 60 knives extend, like the knives k and l to the whole length of the motion, and are carried by the angular rocking arm l^3 , l^4 mounted adjacent the knives k and l . The arms l^3 , l^4 carry rollers l^4 , l^5 , which, under the pressure of their springs l^5 , l^6 roll on inclined

ways k^6 , l^6 carried by the knives l , k , respectively. The oscillation of the auxiliary knives l^2 and l^3 is controlled by stops s , s^2 engaging the inclined ways k^6 , l^6 . These stops, as shown in the drawings, are in the 70 form of bolts adjustably mounted in lugs r projecting from the lower and upper faces respectively of the auxiliary knives l^2 , l^3 , so that they can be moved toward and from the inclined ways k^6 , l^6 . Said inclined ways and 75 said arms are mounted on the knives k , l of each side of the whole of the shedding bars outside of the active part of the knives.

The shedding bars c and c^1 are provided with notches c^9 and c^{10} with which engage 80 the auxiliary knives l^2 , l^3 for holding the shedding bars at the moment of their unhooking and thus avoid an abrupt return of the closed shed.

At the moment of the unhooking of the 85 shedding bar c from its lifted position and of the shedding bar c^1 from its lowered position (see Fig. 3), the tension of the warp threads on the heddles a , a^1 , acting on the supports by the connecting bars z , tends to 90 cause the abrupt returning of the shedding bars c and c^1 , respectively, from their upper and lower positions. This is prevented by the knives l^2 and l^3 , the rollers l^4 , l^5 of which are out of engagement with the inclined ways k^6 , l^6 engaging under the action of the springs l^5 , k^5 , the notches c^9 , c^{10} of the shedding bar c and c^1 which are unhooked. The knives l^2 and l^3 thus accompany the shedding bars, holding them up a 100 little farther than half of the travel, that is to say, up to the moment when the tension of the warp threads ceases to exert action on the shedding bars, owing to the heddles a , a^1 of the harness having returned to their 105 intermediate position A, A (Fig. 5). When the parts are in this position, the inclined ways l^6 , k^6 engage the rollers l^4 , k^4 , and rock the auxiliary knives l^2 , l^3 which are released from the notches c^9 , c^{10} of the shedding bars c and c^1 , the latter are then moved to their new hooking positions (respectively with the lower position and the lifted position) by the knives l and k , thus opening 110 the shed up to the position shown in Fig. 4. 115

Having thus described my invention, I claim as new and desire to secure by Letters Patent:

1. A double shedding motion for open 120 shed weaving looms, comprising shedding bars, a lowering and lifting knife actuating said shedding bars, a series of latches holding the shedding bars hooked in the lifting position, a series of latches holding said shedding bars hooked in their lowering position, a support serving as a guide for each shedding bar during their transverse sliding under the action of the needle of the needle card, and members connecting the support with the rocking levers of the loom, 125 130

said support sliding only in the direction of the traction of the connecting members joining said support with the rocking levers.

2. A double shedding motion for open shed weaving looms, comprising shedding bars, a lifting knife, a lowering knife, said knives actuating said shedding bars, a series of latches holding the shedding bars hooked in their lifting position, a series of latches holding said shedding bars hooked in their lowering position, a support serving as a guide for each shedding bar during its transverse sliding under the action of the needle on the needle card, and metallic bars connecting the support with the rocking levers of the loom, said support sliding only in the direction of the traction of the said connecting bars, said support and shedding bar having engaging inclined surfaces to facilitate the transverse sliding of said shedding bars on their supports.

3. A double shedding motion for open shed weaving looms, comprising shedding bars, a lifting knife, a lowering knife, said knives actuating said shedding bars, a series of latches holding the shedding bars hooked in their lowering position, another series of latches holding the shedding bars hooked in their lifting position, and two auxiliary knives mounted to rock, one on the lifting knife, the other on the lowering knife, said auxiliary knives engaging at the moment of unhooking the shedding bars, corresponding notches in said shedding bars, so as to accompany them and retain them when they

are unhooked up to half of their travel, in order to prevent the abrupt return motion to the position of the closed shed under the action of the tension of the warp threads.

4. In a double shedding motion for open shed weaving looms, comprising shedding bars, a lifting knife, a lowering knife, said knives actuating said shedding bars, a series of latches holding the shedding bars hooked in their lowering position, a series of latches holding the shedding bars hooked in their lifting position, two auxiliary knives mounted to rock, one on the lifting knife, the other on the lowering knife, said auxiliary knives engaging, at the unhooking moment of the shedding bars, corresponding notches in said shedding bars, so as to accompany them and to hold them when they are unhooked up to half their travel, for preventing their abrupt return motion to the position of the closed shed under the action of the tension of the warp threads, inclined ways mounted on the lifting and lowering knives serving to disengage said auxiliary knives from the notches of the shedding bars from the moment that the latter are no longer attracted by the tension of the warp threads.

In testimony whereof I have signed my name to this specification, in the presence of two subscribing witnesses.

GEORGES ELIE LEVY.
